UNITED STATES PATENT OFFICE.

MORITZ EISNER AND JOSEPH MENDELSON, OF PHILADELPHIA, PA.

DESIGN FOR A STAND.

SPECIFICATION forming part of Design No. 16,380, dated November 10, 1885.

Application filed August 27, 1885. Serial No. 175,514. Term of patent 34 years.

To all whom it may concern:

Be it known that we, MORITZ EISNER and JOSEPH MENDELSON, both citizens of the United States, residing in the city and county of Philadelphia, State of Pennsylvania, have 5 invented and produced a new and original Design for a Stand, of which the following is a specification, reference being had to the accompanying photographic illustrations, forming part thereof.

The leading feature of our design is a stair-shaped stand having rings extending from one side to the other.

A represents a wire stand, the sides *a* where- 15 of are stair-shaped.

B represents rows of horizontally-arranged rings, which extend from one side of the stand to the other.

The top cross-bar extends from one of the 20 sides *a* to the other side, and E represents forks extending upward from the sides *a*. The bottom cross-bar, F, also extends from one of the sides *a* to the other side, and G are the feet 25 extending downward from the said sides *a* and the ends of the cross-bar F.

H represents the prop of the stand.

We have shown and described in an application, Serial No. 175,519, filed August 27, 1885, a design for a stand having stair-shaped side pieces, rings B, and twisted necks, which we do not claim herein; but

What we do claim is—

1. A design for a stand having stair-shaped sides *a*, rings B, top cross-bar, D, and bottom cross-bar, F, substantially as shown and de- 35 scribed.

2. A design for a stand having stair-shaped sides *a*, rings B, top cross-bar, D, bottom cross-bar, F, fork E, and feet G, substantially as shown and described.

MORITZ EISNER.
JOSEPH MENDELSON.
